(57) **CLAIM**

The ornamental design for remote controller with display, as shown and described.

DESCRIPTION

FIG. 1 is a perspective view of a remote controller with a display in which various settings are displayed, showing my new design;

FIG. 2 is a front view thereof;

FIG. 3 is a rear view thereof;

FIG. 4 is a top plan view thereof;

FIG. 5 is a bottom view thereof;

FIG. 6 is a left side view thereof; and,

FIG. 7 is a right side view thereof.

The dashed broken lines showing of the remote controller with display are for the purpose of illustrating the settings in the display, and form no part of claimed design; and the dash-dotted broken lines are for the purpose of illustrating light emission around the display and form no part of claimed design.

1 Claim, 3 Drawing Sheets
